(57) **CLAIM**

The ornamental design for a portion of a lanyard connector, as shown and described.

DESCRIPTION

FIG. 1 is a perspective view of a portion of a lanyard connector showing my new design;

FIG. 2 is a front elevational view of the portion of a lanyard connector shown in FIG. 1;

FIG. 3 is a rear elevational view of the portion of a lanyard connector shown in FIG. 1;

FIG. 4 is a first side view of the portion of a lanyard connector shown in FIG. 1;

FIG. 5 is a second side view of the portion of a lanyard connector shown in FIG. 1;

FIG. 6 is a top view of the portion of a lanyard connector shown in FIG. 1; and,

FIG. 7 is a bottom view of the portion of a lanyard connector of the lanyard connector shown in FIG. 1.

The uneven broken lines in FIGS. 1-7 represent the remaining portion of the lanyard connector. The uneven broken lines are for illustrative purposes only and form no part of the claimed design.

1 Claim, 3 Drawing Sheets

FIG. 1

FIG. 2**FIG. 3**

FIG. 4**FIG. 5****FIG. 6****FIG. 7**
